The ornamental design for an exercise squat rack, as shown and described.

DESCRIPTION

FIG. 1 is a perspective view of an exercise squat rack, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and

FIG. 8 is a bottom plan view thereof.

FIG. 9 is an enlarged view of portion of FIG. 1;

FIG. 10 is another enlarged view of portion of FIG. 1; and, FIG. 11 is an enlarged view of portion of FIG. 2.

The broken line showing of the exercise squat rack is for the purpose of illustrating article and forms no part of the claimed design.
